CLOSURE HEAD WELDED FOR PRESSURE VESSELS

Anderson W. Harris, Chattanooga, Tenn., assignor to Combustion Engineering Company, Inc., New York, N. Y.

Application February 10, 1943, Serial No. 475,375

1 Claim. (Cl. 220--3)

This invention relates to pressure vessels. Metallic vessels used for retaining fluids under pressure, such as drums for oil stills and steam boilers, are usually cylindrical and have the ends closed by heads formed into a full hemispherical shape; or other full formed heads are used such as semi-elliptical shape in section or a fully dished head.

The stresses in elliptical and dished heads are greater than in hemispherical heads, due to their shape. Consequently hemispherical heads may be of thinner and less costly material. When necessary to put in the head an opening that requires reinforcement, the reinforcement required in a hemispherical head is less. However, full hemispherical heads of conventional construction, when made from one plate, involve a forming operation that is difficult and costly. The dies over which the metal is bent to form the heads are costly and it has been found that the head may "freeze" to the male dies and is difficult to remove.

Full elliptical and full dished heads must have a flange or straight portion around their rim to avoid excessive concentration of stresses at the point of juncture with the shells to which they are attached. Furthermore the stresses at and adjoining the joint are difficult to properly analyze.

It is an object of this invention to provide an improved drum head which overcomes the difficulties of forming a conventional hemispherical head, yet provides all of the advantages of a head of that shape.

In the drawing:

Figure 1 is a longitudinal section of part of a drum and its head showing the prevailing construction.

Figure 2 is a similar view of a drum and its head showing the improved construction.

In Fig. 1 the end of the drum shell 1, being thicker than the head is machined down in thickness to provide a reduced portion 2 of the same thickness as the formed head 3. The drum end and the head are fastened together by a weld 4. The head shown has been formed to a full hemisphere in shape but it may be of other equivalent full formed heads, such as a head of semi-elliptical section or a full dished head. In order to overcome the difficulties mentioned above as involved in the forming of a full hemispherical head, I form a head as disclosed in Fig. 2.

Before machining, the end of the drum shell 10 extends in full thickness as shown by the dotted line 11. The end metal is then machined off inside and outside to suitable arced surfaces 5 shaped as shown by the lines 12 to provide a thickness at its end equal to that of the head. The inside surface 12 is substantially that of a sphere and is a continuation of the inside spherical surface of the head 13. For convenience in 10 machining, the part of interior surface 12 beyond the hemisphere may be made conical. Obviously the inside surface 12 may be a substantial continuation of other shaped heads, such as an inside elliptical surface in section. By so 15 shaping the drum end, the joint 14 between the drum and the head may be located to one side of the plane in which the diameter of the semicircle for generation of the spherically shaped head is located. Consequently the head 20 itself is less than a hemisphere with proportionately less material to be worked; it may be formed relatively easily from a plate by pressing it between dies without becoming frozen onto the male die because that portion of the full 25 spherical head, which seizes the male die upon shrinking, is not present but has been incorporated in the shell. Furthermore, the location of joint 14, being within the spherical limits of the head, is subject to known spherical stresses 30 while the stresses adjoining the joint of the full spherical head to the main body as shown in Fig. 1 are of doubtful analysis.

What I claim is:

35 In a metallic pressure vessel; a concavo-convex, monolithic head portion constituting less than a semi-ovoid, hemisphere or the like; a hollow body portion of annular cross-section of metal thicker than that of the head having an integral end portion abutting the latter, said 40 end portion being reduced to a corresponding thickness with its interior and exterior surfaces having radii corresponding to those for the head and constituting continuations thereof over a distance back from the end edge of the body 45 portion sufficient to complement the head in forming a semi-ovoid or hemispherical end portion for the vessel; and a weld joint between the body portion and head lying outside the plane containing the diameter of the semicircle for generation of the spherical surfaces of said head.

ANDERSON W. HARRIS.
